UNITED STATES PATENT OFFICE.

ALBERT W. HALE, OF NEW BRITAIN, CONNECTICUT.

MEAT-MINCER.

Specification forming part of Letters Patent No. 23,246, dated March 15, 1859; Reissued December 26, 1865, No. 2,136.

To all whom it may concern:

Be it known that I, ALBERT W. HALE, of New Britain, State of Connecticut, have invented a new and Improved Machine for 5 Cutting or Mincing Meat, Vegetables, &c.; and I do hereby declare that the following is a full, clear, and exact description thereof, reference being had to the accompanying drawings and to the letters of reference 10 marked thereon and making a part of this specification.

The nature of my invention consists generally in the arrangement and use of one or more grooved cylinders or rollers, revolving 15 in a grooved or ribbed case, and acting against a stationary knife, whereby I produce a machine economical and simple in construction; not liable to get out of order, and which can be easily kept sweet and 20 clean for use.

Figure 1, is a perspective view, the upper case being removed or open, showing the construction of the case, the position of the grooved cylinders or rollers and also the 25 place of discharge of the minced article. Fig. 2, is a view of the lower case, one cylinder being removed, showing the position of the knife, and also the construction of the lower case, or cylinder bed. Fig. 3, is a view 30 of that portion of the lower case, holding the knife. Fig. 4, is an end view of the cylinders and knife in position; one cylinder being changed end for end, so as to show both the greatest and shallowest depths of the 35 grooves. Fig. 5, is a side view of the machine with a stuffer attached. Fig. 6, is a sectional view of a machine with a single cylinder, instead of two.

The upper and lower cases A, and B, are 40 constructed or fitted with ribs or projections a, a, Figs. 1, 2, upon their inner concave surfaces, which form, when the cases are in position or closed, a continuous spiral rib or screw, inclining forward and toward the 45 orifices b, b, at which the minced article is discharged. These ribs a, a, may have any angle or inclination, more or less, as preferred, and as desired to have the meat, &c., pass slower or faster through the machine, 50 but I generally prefer to give them such an inclination, that in passing once around, they shall have advanced a distance about equal to the diameter of the feeding orifice C, in order that anything fed into the machine

would naturally, in a single revolution, pass 55 beyond the orifice C.

The cylinders or rollers D, and E, are of such a size as very nearly to fill the space between the cases A, and B, when closed, and so as to prevent the passing of anything of 60 much size or bulk between the case, and the rollers. These cylinders have also a number of spiral grooves e, e, running lengthwise, the spiral course of which may be greater or less as desired or found most convenient. 65

The drawings represent five such grooves upon each cylinder, but the number is merely arbitrary, and may be varied, as desired. These grooves are also not of uniform size, but vary in depths as seen in Figs. 1, 4, 70 their depth at one, or as it may be called the front end, being about equal to the distance from the shaft or axle F, to the periphery of the cylinder, and thence gradually diminishing toward the other end, until the bottom of the groove nearly reaches the periphery of the cylinder, as seen in Fig. 4, its distance here being more or less as it may be desired to have the thing cut coarser or finer, as from these ends of the grooves 80 everything is discharged from the machine, and nothing can pass out until cut small enough to pass through these diminished orifices. From this construction of the cylinders and their grooves, it is readily apparent that pieces of meat &c., while of a largish size are prevented from passing into the shallowest parts of the grooves, and are continually pressed backward, and carried by the revolution of the cylinders toward 90 the knife or knives, hereafter mentioned, and will only be discharged from the machine, when cut fine enough to pass out of the apertures b, b, made by the shallowest ends of the grooves with the surrounding 95 case. The diminishing of the area of the grooves or spaces between the flanges of the cylinders D, and E, may also be effected by decreasing the diameters of such cylinders at one end, thus giving them the form of a 100 frustum of a cone; and in such cases making the outer cases to fit to such form; and also in other ways. The particular form and arrangement of the parts is not material so long as this feature of diminishing 105 the sectional area of the grooves, or spaces between the flanges, is substantially preserved. The number of grooves and flanges

may also be greater at one end of the cylinder than at other, and the flanges may have a variable twist. The flanges or highest parts of such grooves, make at the periphery 5 of such cylinder's edges *e*, *e*, which act against the knives referred to, with a drawing or shearing cut.

The position of the cylinders D, and E, in the cases A, and B, is such that the 10 flanges or edges *e*, *e*, will lap a little upon each other, as shown in Figs. 1 and 4, so that the cylinder operated by the crank F¹, will communicate motion to the other without gearing, and thus cause both cylinders to 15 revolve toward the knives placed between them as hereafter described, carrying with them by means of the grooves *c*, *c*, the article to be cut, and which the depth of the grooves, as before set forth, prevents from 20 passing forward, and out of the orifice *b*, *b*, until it is sufficiently cut and minced. Instead however of constructing the cylinders with grooves as described, a shaft or axle 25 may have flanges radiating from it, or placed tangentially upon it, which shall act upon the knife H, in the same way, as the edges *c*, *c*, the spaces between such flanges being so filled, or the depth of the flanges being so diminished, as substantially to 30 secure the taper of the groove above referred to. Nor is the spiral direction of the grooves or edges, as above described, absolutely essential, as their arrangement may be varied by making the flanges of the 35 revolving cylinder parallel to its axis, and inclining the edge of the knife, and so adjusting the cylinders, as to preserve and secure the benefits and advantages of the shearing cut of such edges on the knife, as 40 described.

The position of the knife or knives H is shown in Fig. 2, and also an end view in Fig. 4. They extend the length of the cylinders, and rest in a slot or recess in the 45 lower or under case B, directly between the cylinders—shown in Fig. 3, and are of such a height that the edge *h*, will be at that point or line where the grooved cylinders leave each other. As these cylinders revolve 50 therefore, their flanges *e*, *e*, will be constantly acting upon the edge of the knife, with a drawing or shear cut, thus acting most easily and effectually.

The slot or recess in which the knife or 55 knives rest may be a little tapering on one side, so as to allow the insertion of a small wedge *f*, Fig. 3, to fasten the knife; or such slot may be of uniform width and broader, with tapering wedges placed on each side 60 of the knife, operated by screws at either end, so that the position of the knife may be adjusted as desired; or such slot may have a width uniform and a little greater

than the thickness of the knife, so that the knife may rest in it loosely, its edge being 65 kept in position by contact with the cylinders.

In order to give the edge of the knife the proper position, in respect to the cylinders D, and E, the ends of the back of the blade 70 are beveled or chamfered, as shown by the dotted lines *f'*, *f'*, Fig. 2, against which work screws *g*, *g*, to elevate the knife, as necessary; or the blade may rest upon a small steel or other spring underneath it, or 75 on a strip of rubber or other elastic material, or upon a wedge operated from either end to insure the contact of the edge. The same principle of operation may be secured by the use of a single revolving cylinder, 80 though of course the capacity of the machine will be somewhat less. Such an arrangement is shown in Fig. 6. In such case the ribbed cases, and grooved and flanged cylinder will be the same as above 85 described, but the knife H, will stand at one side of the cylinder D', and will be supported at its ends, and perhaps at its middle, and the article cut will pass outside of the knife, into a cavity or recess G, cast 90 at one side of the cases for such purpose, and from thence under the knife, and again in contact with the cylinder D', and by it be again carried to the knife. A more rapid operation may be obtained by placing a 95 knife on each side of such cylinder.

By attaching a funnel or stuffer J, as shown in Fig. 5, to the machine, casings of any kind can be filled at the same time the meat is minced. Without the stuffer, the 100 machine is fitted for the ordinary uses of cutting and mincing.

The several parts of the machine may be cast, and are at once fit for use, except that the knife may be better rolled out the desired 105 shape, and tempered or hardened; and the cylinders may be cast, rolled, or forged. The whole is simple in construction, not liable to get out of order, and every part is easily cleaned and kept sweet for use. 110

What I claim as my invention and desire to secure by Letters Patent is—

A cutting or mincing machine operating by means of a cylinder or cylinders having tapering grooves extending from end to end, 115 in combination with, and revolving in fluted or ribbed cases A, and B, and acting against a stationary knife or knives placed in a plane parallel with the axes of the cylinders, the whole arranged substantially as and for 120 the purposes set forth.

ALBERT W. HALE.
